UNITED STATES PATENT OFFICE.

SYLVANUS B. ROY, OF WORCESTER, MASSACHUSETTS; SERENA L. ROY, ADMINISTRATRIX OF SAID SYLVANUS B. ROY, DECEASED, ASSIGNOR TO B. S. ROY & SON COMPANY, A CORPORATION OF MASSACHUSETTS.

AUTOMATIC DOOR-OPERATING DEVICE.

1,204,318.

Specification of Letters Patent.

Patented Nov. 7, 1916.

Application filed July 19, 1915. Serial No. 40,562.

To all whom it may concern:

Be it known that I, SYLVANUS B. Roy, a citizen of the United States, residing at Worcester, in the county of Worcester and State of Massachusetts, have invented a new and useful Automatic Door-Operating Device, of which the following is a specification.

This invention relates to a door operating means suitable for garages and other buildings generally, and to controlling devices and combinations by which the opening and closing of the door is rendered certain, definite, safe and automatic, so that it can be accomplished by the mere passage of a vehicle over a treadle or the operation of the treadle or equivalent device in any other manner, and yet can be controlled by hand by means of push-buttons or equivalent devices.

The principal objects of the invention, in addition to these, are to provide adequate means by which heavy or light doors can be operated, preferably by hydraulic power, and controlled in such a way that the opening and closing controlling mechanism respectively, as for example, electrical connections, cannot be operated by push buttons or treadle when the door or both doors, if the invention is applied to double doors, shall be fully opened or fully closed; also to provide means whereby whenever the doors are opened, the operation of the treadle will start them to close and vice versa, the operation of the closing button will cause them to start to close but the operation of the opening push-button can have no effect and vice versa; to provide means whereby when the doors are opened, the opening solenoid, or other controlling mechanism, cannot be operated in any way or when closed the closing solenoid cannot be operated; and to provide means whereby the manual manipulation of any feature of the switch board operating solenoids or other elements which are exposed cannot put the mechanism out of commission or start the operation of the doors except in the prescribed manner.

The invention also involves a system of terminal switches which are operated and controlled by the doors in such a way as to secure one of the above mentioned results, namely, permit of the operation of

starting the opening or closing only when both of a pair of doors are fully closed or open, as the case may be.

Further objects and advantages of the invention will appear hereinafter.

Reference is to be had to the accompanying drawings in which,

Figure 1 is a plan of a portion of the plan constructed in accordance with this invention showing the treadle mechanism and illustrating the wall of the building and the double doors in horizontal section; Fig. 2 is an elevation of the top of the doors showing the mechanism on the inside thereof for operating them; Fig. 3 is a plan on enlarged scale of a portion of the mechanism shown in Fig. 1 illustrating the support for one corner of the treadle; Fig. 4 is a sectional view on the line 4—4 of Fig. 3; Fig. 5 is a sectional view on enlarged scale on the line 5—5 of Fig. 1; Fig. 6 is an inside elevation of the hydraulic door operating mechanism being a part of Fig. 1 on enlarged scale; Fig. 7 is a similar view of another portion of the same mechanism also showing the door switch; Fig. 8 is an elevation of the opening door switch and connected parts; and Fig. 9 is a front elevation of the switch board showing the electrical connections and the hydraulic mechanism controlled thereby and also showing diagrammatically the electrical wiring of the whole plant.

Referring more particularly to Figs. 2, 6 and 7, the invention is illustrated as being applied to a double door system consisting of two doors 15 and 16. It is to be understood, however, that many features of this invention can be applied to a single door in a similar manner. These doors as usual are designed to move together to close and to move oppositely to open and are supported from above on a track hanger 17. This track hanger is not illustrated in detail, as it can conveniently be made in an ordinary form in which it has longitudinal slots through the bottom, up through which project brackets 18 attached to the doors. These brackets have wheels or rollers thereon, not shown, but located inside the track hanger and supported thereby.

For the purpose of operating the doors, two hydraulic cylinders 19 and 20 are

shown arranged horizontally above the doors adjacent to the track hanger. These are supplied with water through a system of piping as follows: A supply pipe 21 (Fig. 9) controlled by main valve 22, supplies water to a pilot valve casing 23 which is of well-known type and need not be described in full herein, but it has pistons therein on rods 24 and 25 which control by their position the passage of water from the supply pipe 21 to two pipes 26 and 27, which will be called here the opening pipe and closing pipe, respectively. On Fig. 9 is shown an exhaust pipe 28 which is connected through the valve with the pipes 26 and 27 to carry off the waste and allow the water to flow out of these pipes and out of the cylinders when necessary. These connections are not shown in detail, as they do not constitute part of this invention.

The pilot valve is shown as controlled and operated electrically, by an opening solenoid 6 and a closing solenoid 7, having plungers 8 and 9, respectively. The two plungers 8 and 9 are pivotally connected with two pivoted levers 10 operating independently of each other and these levers are respectively connected by links 11 with the piston rods 24 and 25, respectively. The exhaustion of the opening or closing solenoid therefore will operate one of the piston rods 24 or 25 and admit water to one of the pipes 26 or 27 and open the other to the exhaust.

In the drawings, the doors are shown as closed and just ready to open, the arrows indicating the motion which the parts will have as the doors start to open. Now the pipe 26 is connected with the left-hand end of the cylinder 20 and the pipe 27 with the right-hand end thereof, while the pipe 26 is connected with the right-hand end of the cylinder 19 and the pipe 27 with the left-hand end thereof. In each of these cylinders there is a piston as 29 and 30. They have piston rods 31 and 32, respectively. Piston rod 31 is connected by means of a bracket 33 with the left-hand door 15, while the piston rod 32 is connected by a bracket 34 with the right-hand door 16. This connection is positive but adjustable if desired.

It can be seen that with the parts in the position shown in the drawings, the connection of the pipe 26 with the supply pipe 21 will cause water to flow to the left-hand side of the piston 30 and the right-hand side of the piston 29, and consequently will move the left-hand door 15 to the left and the right-hand door 16 to the right. In other words, it will open the doors. At the same time, of course, the pipe 27 is connected by the pilot valve with the exhaust so as to allow the water already in the two cylinders on the opposite sides of the pistons to run out without resistance.

It is for controlling the operation of the

parts just described that the electrical connections are provided, and as has been stated, two push-buttons 37 and 38 are shown, the former having only the function of starting the doors to open and the latter only the function of starting the doors to close, but ordinarily the operation of the doors is controlled by a treadle 40 which has the function of starting the doors either to close or open according to their position when it is depressed. This treadle is shown as supported on springs 41 located in casings 42 within a pit in the ground, and as provided with a lever 43 pivoted on a standard 44 and adapted when the treadle is depressed to allow a roll 45 to rise and thus depress the other end of the lever 46 on which this roll is located, a spring 47 preferably being used to operate the lever 46. The depression of the inner end of this lever causes it to come into electrical contact with a metallic member 48. The two members 46 and 48 are connected with two wires 49 and 50, respectively, and obviously bring these wires into contact. These parts are represented diagrammatically in Fig. 9, which shows a switch board 51 having binding posts 1, 2, 3; 4 and 5, and this diagram will now be described. The main switch 52 is shown as having terminals as usual connected directly with fuses 53. One of these fuses is directly connected with the binding post 3, which in turn is connected by the wire 50 with the terminal 48. It is also connected by a wire 54 with one contact of each of the two push-buttons 37 and 38 so that these push-buttons are in multiple with each other, but each in series with the plus fuse 53. The other contact forming part of the push-button 37 is connected by a wire 55 with a binding post 5. It is also connected with a terminal 56, the purpose of which will be described later. In a similar manner the other terminal of the push-button 38 is connected by wires 57 with binding post 1 and with a terminal 58 similar to the terminal 56.

The binding posts 5 and 1 are connected respectively with two switches 60 and 61 which we designate the door switches. The wire 49 has two branches each passing to the pole of one of the switches 60 and 61 which is connected with the binding posts 5 and 1 respectively.

Each one of the switches 60 and 61, as indicated in Figs. 7 and 8, comprises a terminal 62 which is stationary, and a reciprocating plunger 63 or 63^a operating a lever having a terminal 630 or 631 thereon normally moved against the terminal 62 by a spring 64. In connection with the switch 60 there is a lever 65 which is carried by a sliding plate 66 normally moved yielding by a spring 67 away from its plunger 63. One end of this lever is in a position to be

engaged by a bracket 68 on the left-hand door 15 when the latter opens to its limiting position. This, however, has no effect on the plunger 63 for the reason that the lever 65 is capable of turning about the end of this plunger as a fulcrum, and in turning its opposite end engages a lever 69 pivoted on a stationary pivot on the same plate 70 on which these parts are mounted. Therefore, this action simply sets the lever ready to be operated. This lever is connected by a wire or cord 71 with a lever 72 at the opposite end of the doors, which lever is pivoted on a bracket 73. Now when the right-hand door 16 opens to its limiting position, its bracket 34 will engage this lever 72 and push it to the right, thus pulling on the cord or wire 71 and swinging the lever 69 accordingly. The lower end of this lever then acts on the upper end of the lever 65 and pushes it against a stop 74. As the lower end of the lever 65 is still held against the bracket 68, this lever will then be positively turned about the latter as a fulcrum and the plunger 63 forced inwardly and contact broken between the lever 630 and the metallic contact 62. It will be obvious that if the door 16 opens first, the plunger 63 will not be operated until the left-hand door 15 also opens to its limit, so that this contact cannot be broke automatically until both doors are wide open. Now these contacts 62 and 630 are connected in series with the opening solenoid 6 so that when both doors are wide open this contact 62-630 is open and the solenoid 6 ceases to be operative.

There is a similar arrangement for stopping the closing solenoid 7. This is shown in Fig. 7 and in that case the plunger 63^a, which is made the same as the plunger 63 previously described, is provided at its end with a lever 77 carried by a sliding plate 78 and pulled away from the plunger 63^a normally by a spring 79. Two levers 80 and 81 are pivoted on stationary pivots on the plate 82 which supports these parts and they are connected by wires or cables 83 and 84, respectively, with a lever 85 and a lever 86. The lever 85 is connected by wire, chain or cable 87 with a lever 88. The lever 88 is in position to be engaged by the bracket 34 when the door 16 comes to its fully closed position, and the lever 86 is in position to be engaged and operated by the bracket 33 when the door 15 comes to its fully closed position. In each case the lever 80 or 81, as the case may be, is swung to the right at its outer end and its inner end is swung to the left against the lever 77. The operation of either one of these levers will not result in the operation of the plunger 63^a for the reasons described in connection with the other case, but the operation of both of them, either simultaneously or one after

the other, will force that plunger in and break the connection at this point (62-631).

When the contacts 62-630 of the door switch 60 are together it connects two conductors 90 between the binding posts 4 and 5. When the similar contacts in the door switch 61 are together it connects two conductors 91 between the binding posts 1 and 2. The conductors 90 are in series with the opening solenoid 6 and the conductors 91 in series with the closing solenoid 7. Consequently, it will be obvious, without further describing the mechanism, that the opening solenoid is dead when both doors are fully open, and that the closing solenoid is dead when both doors are fully closed.

In order to guard against any chance of getting the parts into such condition that the doors can be started in the wrong direction, and especially to provide means whereby when one solenoid is in operation or excited, the other is positively rendered dead by that condition, two other pairs of conductors 92-92^a and 93-93^a are provided. The conductors 92 and 92^a are in series with the opening solenoid 6 and with a contact-making arrangement having two contacts 94 and 95, the contact 95 being fixed and the contact 94 being mounted on a spring 96. A pin 97 is provided over which is a spring 98. The plunger or piston 9 of the closing solenoid 7 normally presses down on this spring 98 and holds the spring 96 down through the instrumentality of the pin 97 so as to keep the contacts 94 and 95 in engagement with each other, but when the plunger 9 starts to rise, the springs 98 and 96 are automatically allowed to rise and the contacts 94 and 95 separate so that the solenoid 6 is disconnected from the power by the separation of these contacts. The solenoid 7 is controlled in the same way by the contacts 99 and 100, and the plunger 8 of the solenoid 6, the connections of which through the wires 93 and 93^a need not be described in detail, as they correspond in all respects with the circuit just described. The contact 95 is connected with the binding post 4 to which one wire 90 is also connected in series. The contact 100 is connected with the binding post 2, with which one wire 91 is connected in series, so that the door switches are in series with their respective cut-outs 94-95 and 99-100.

In view of the fact that the depression of the treadle 40 or the depression of either one of the push buttons 37 or 38 for the purpose of operating the doors is ordinarily only momentary, means is provided whereby the closing or opening solenoid, as the case may be, will continue to be supplied with current after the treadle or push button which starts the machine is released. It is for this purpose that the binding post 1 is

connected with the terminal 58 and the binding post 5 with the terminal 56. Furthermore, two levers 101 are connected with the two levers 10 so as to be raised with them, 5 and provided with carbon block terminals 102 which are adapted to engage the terminals 56 and 58, respectively, when these arms are raised by the operation of their respective levers 10. Both of these arms 10 101 are connected by a wire 103, with the binding post 3 and thus with one side of the main circuit.

Assuming that the opening solenoid 6 has just operated and the push button or treadle 15 switch has opened its contact so that current is no longer supplied therethrough to the solenoid 6, the current will still flow to it through these elements in order, 53, 3, 54, 103, 101 at the right, 102, 56, 55, 5, 90.

20 Although the operation of the device is thought to be clear from the above description of the respective parts, yet I shall proceed to describe certain features of it in a different order. Let it be assumed that the 25 doors are closed together, as shown in the drawings, and that an automobile passes over the treadle 40. The depression of this treadle makes the contact 46-48 and sets up a current from the plus side of the line 30 through the fuse 53, binding post 3, wire 50, contacts 48 and 46 to either one of the door switches 60 or 61 which happens to be closed. As has previously been stated, only 35 one of these can be closed at a time when the doors are in their normal condition, entirely closed or entirely open.

If the doors are fully closed, as indicated in the drawings, the door switch 61 will be open but the switch 60 will be closed and the 40 circuit can be completed through it to the wire 90 from the binding post 3. Incidentally, the binding post 5 and the terminal 56 will be connected through the treadle with the plus side of the line, but this will have no present effect. The current, however, will pass 45 through the wire 90, binding post 4, wire 92, contact 95 and contact 94. Now this results in bringing the opening solenoid 6 into the circuit which is complete from its other 50 end directly to the fuse 53 and minus side of the main circuit. The immediate effect of the excitation of this solenoid is to start the plunger 8 to rise. This pulls up on one of the levers 10 and the piston rod 24 and 55 admits water from the pressure side of the system to the pipe 26. This water will flow in behind the two pistons 29 and 30 and push them in opposite directions so as to start the doors to open. Another result of the 60 raising of the plunger is to bring the contact 102 at the right into engagement with the contact 56 and this forms a shunt circuit around the contact 46-48, which immediately opens ordinarily. This continues to 65 supply current to the solenoid 6.

In case the opening push-button 37 had been pressed instead of the treadle, the result would have been the same, because the current would have been brought from the left-hand fuse 53, binding post 3, wire 54, 70 through the push-button 37 to the wire 55, door switch 60, wire 90, contacts 94 and 95 to the solenoid 6 and back to the other fuse 53 and the minus side of the line. All the other effects would have been the same. 75 From this it will be seen that in case the doors are closed, as shown in the drawings, the closing of the button contact 88 cannot cause any trouble because the other solenoid 7 is cut out by the open door switch 61. 80 Furthermore, the manual raising of either one of the plungers 8 or 9 cannot cause any trouble, because in either case the contacts 99-100 or 94-95 will be automatically opened and if the contacts 56 and 102 or 58 85 and 102 are engaged, the wrong solenoid cannot be operated because it is cut out in the manner just described and is also cut out by one of the door switches, if the doors are either fully open or fully closed, and, if 90 for example, both of the plungers 8 and 9 are raised to make these contacts, the doors will start to open or close in accordance with their position when the circuit is completed.

Although I have illustrated and described 95 only a single embodiment of the invention and shown it as applied to a hydraulic system, electrically controlled, and shown it as applied to a double door, I am aware of the fact that the invention is not limited to these 100 or to the other features shown in the drawings, but that modifications can be made therein by any person skilled in the art without departing from the scope of the invention as expressed in the claims. Therefore, I do not wish to be limited in these respects, but

What I do claim is:

1. The combination with a pair of sliding doors, of a pair of parallel hydraulic cylinders, each having a piston connected with one of the doors, means for simultaneously causing said pistons to move in opposite directions to close or open both doors, and means whereby if one door opens or closes 110 before the other said first-mentioned means cannot be operated to change the direction of motion of either piston until the second door comes to its fully open or closed 115 position.

2. The combination with a door and a cylinder and piston for operating it, of electrical connections for controlling the operation of the piston comprising a switch, yielding means for normally holding the switch closed, a lever independent of the door connected with the switch for opening it, and means on the door for operating said lever to tend to open the switch when the door comes to its open position.

3. The combination with a door and a cylinder and piston for operating it, of electrical connections for controlling the operation of the piston comprising a switch, yielding means for normally holding the switch closed, a lever independent of the door connected with the switch for opening it, and means on the door for operating said lever to tend to open the switch when the door comes to its closed position.
4. The combination with a pair of doors, of a piston and cylinder for each door for operating the same, a door switch, means operated by the two doors for positively opening said door switch only when the two doors are both in one of their extreme positions, and means connected with said door switch whereby when it is closed the cylinders can be connected with a source of fluid pressure for operating the doors from said extreme position.
5. The combination with two doors and means for operating them, of a switch for controlling the opening of the doors, a switch for controlling the closing of the doors, and means whereby the opening switch is operated to be opened only when both doors are fully open, and the closing switch is operated to be opened only when both doors are fully closed.
6. In a door operating mechanism, the combination with a pair of doors, of two cylinders and two pistons connected with said doors for operating them, means for controlling the operation of said pistons and cylinders, said means comprising two circuits, each having a door switch in series therein, means connected with said doors for operating said door switches to open one of them only when both doors are fully open or fully closed, and connections in series with the respective door switches whereby said pistons and cylinders are connected with a source of fluid pressure, the connections being controlled by said door switches.
7. The combination with a pair of doors, of a piston and cylinder for each door for operating the same, an opening door switch, means operated by the two doors for positively opening said door switch only when the two doors are both entirely open, and means connected with said door switch whereby when it is closed the cylinders can be connected with a source of fluid pressure for the opening of the two doors.
8. The combination with a pair of doors, of a piston and cylinder for each door for operating the same, a closing door switch, means operated by the two doors for positively opening said door switch only when the two doors are both entirely closed, and means connected with said door switch whereby when it is closed the cylinders can be connected with a source of fluid pressure for the closing of the two doors.
9. In a device of the character described, the combination of two doors mounted to move in alignment with each other, two pistons and cylinders connected with said doors for simultaneously opening them or simultaneously closing them, means for controlling the operation of said cylinders comprising two door switches each constructed and arranged to prevent the operation of the pistons in one direction when open, means for opening one of said door switches when both the doors are fully open, and means for opening the other when both doors are fully closed.
10. In a device of the character described, the combination of two doors mounted to move in alignment with each other, two pistons and cylinders connected with said doors for simultaneously opening them or simultaneously closing them, means for controlling the operation of said pistons comprising two door switches each constructed and arranged to prevent the operation of the pistons in one direction when open, means for opening one of said door switches when both the doors are fully open, and means for opening the other when both doors are fully closed, one of the two last named means comprising a system of levers co-operating with a door switch and in position to be operated by said doors when they move to limiting position.
11. In a device of the character described, the combination with a pair of doors arranged to operate in alignment and adapted to move toward each other for closing and away from each other for opening, hydraulic means for operating said doors to close or open, electrical means for controlling the hydraulic means, said electrical means comprising an opening door switch and a closing door switch, and means whereby when the opening door switch is open the hydraulic means cannot be operated to open the doors and when the closing door switch is open the hydraulic means cannot be operated to close the doors.
12. In a device of the character described, the combination with a pair of doors arranged to operate in alignment and adapted to move toward each other for closing and away from each other for opening, hydraulic means for operating said doors to close or open, electrical means for controlling the hydraulic means, said electrical means comprising an opening door switch and a closing door switch, means whereby when the opening door switch is open the hydraulic means cannot be operated to open the doors, and when the closing door switch is open the hydraulic means cannot be operated to close the doors, and means for operating each of said door switches comprising a lever having no stationary pivot, means operated by one door for turning the

lever about a movable fulcrum in one direction when that door is in its limiting position, and means operated by the other door for turning the other end of said lever when the other door is in its limiting position, whereby said lever will operate the door switch for opening it and render one of the above mentioned means inoperative.

13. The combination of a plunger which when moved to a certain position is adapted to break a contact, a lever having a movable pivot arranged in contact with the plunger, whereby when pressure is exerted on one end of the lever, the lever will swing about the end of the plunger as a pivot and whereby if the pressure is retained on that end of the lever and the other end of the lever pushed in the same direction the plunger will be forced in to break its contact, an

auxiliary lever for operating one end of the first named lever, a pair of doors, means on one of said doors for operating the first named lever at its first named end, and means on the other door for operating the second lever.

14. The combination with a pair of sliding doors, of a door switch, a lever for opening said door switch, means on one door for setting said lever when that door reaches its limiting position, means on the other door for then operating the lever to open said switch when said other door reaches a like limiting position, and means controlled by the door switch for operating the doors.

In testimony whereof I have hereunto set my hand.

SYLVANUS B. ROY.
